UNITED STATES PATENT OFFICE.

ALTON H. MATTESON, OF CAMBRIDGE SPRINGS, PENNSYLVANIA.

SANDPAPERING-MACHINE.

1,159,696.

Specification of Letters Patent.

Patented Nov. 9, 1915.

Application filed February 9, 1915. Serial No. 7,023.

To all whom it may concern:

Be it known that I, ALTON H. MATTESON, a citizen of the United States, residing at Cambridge Springs, in the county of Crawford and State of Pennsylvania, have invented certain new and useful Improvements in Sandpapering-Machines; and I do hereby declare the following to be a full, clear, and exact description of the invention, 10 such as will enable others skilled in the art to which it appertains to make and use the same.

This invention relates to machines for sandpapering or polishing chair legs or 15 other similar articles; and it consists in the novel construction and combination of the parts hereinafter fully described and claimed, whereby the work is fed automatically to the machine, is smoothed and polished in its passage through the machine, and is finally discharged therefrom.

In the drawings, Figure 1 is an end view of a sandpapering machine constructed according to this invention, the feeding and 25 the centering devices for the work, and some other parts, being omitted for clearness. Fig. 2 is a front view of the machine, partially in section, with the feeding devices and various other parts omitted for clear- 30 ness. Fig. 3 is an end view of one work carrier and the trip mechanism for operating the feeder. Fig. 4 is an end view of the feeder, and it also shows a portion of the supporting devices for the sandpaper, 35 in section. Fig. 5 is a front view of the feeding devices. Fig. 6 is a cross-section through the feed magazine or hopper, taken on the line $\alpha-\alpha$ in Fig. 4. Fig. 7 is a detail plan view of the adjustable guide for the 40 feeder fingers. Fig. 8 is a side view of the same. Fig. 9 is a detail view of a portion of the feeder mechanism, showing the feeder fingers in a different position from that shown in Fig. 4.

The machine is provided with a supporting frame 2 of any approved construction, and a driving shaft 3 is journaled in the frame and provided with a belt pulley 4 for revolving it. The main shaft 5 of the 45 machine is journaled in a bearing 6 on a stationary headstock 7, and in a bearing 8 on a slideable tailstock 9. The tailstock 9 is slideable on the frame 2, and 10 is a screw or other approved means for adjusting its 50 position. A worm-wheel 12 is secured on the main shaft 5, and 14 is a worm secured

on a countershaft 15, which is journaled in bearings on the frame 2. The worm gears into the worm-wheel, and the countershaft is revolved by a quarter-twist belt 16 which 60 passes over a pulley 17 on the driving shaft 3 and over a pulley 18 on the countershaft. Any other approved driving devices may be used in carrying out this invention.

Two work carriers 20 and 21 are mounted to revolve with the main shaft 5. The carrier 20 is keyed fast to the shaft, and the carrier 21 is splined to it so that the distance between the carriers may be adjusted to suit work of different lengths. The 70 carrier 20 has a series of live spindles 22 journaled in it, and arranged in a circle at equal distances apart around its center, and these spindles have belt pulleys 23 secured on them. The spindles 22 have projections 75 24 at one end for engaging with and revolving the work. The carrier 21 has a series of dead spindles 25 mounted in it to correspond with the live spindles 22. The spindles 25 are retractable, and they do not re- 80 volve in bearings, but have centers 26 for the work to revolve on.

The spindles 22 and the work are revolved by means of a belt 27 which passes over the pulleys 23 and over a belt pulley 28 secured 85 on the driving shaft 3. A guide pulley 29 is supported by and journaled in a bracket 30 at the front part of the machine, and it operates to hold the belt 27 clear of the pulleys 23 until the spindles pertaining to 90 them have received the work. A belt-tightener 31 of any approved construction is arranged under the carrier 20 and holds the belt 27 at a predetermined tension.

The carrier 20 is revolved in the direction of the curved arrow in Fig. 1, and the belt 27 is moved in the direction of the straight arrow in Fig. 1, to revolve the spindles. The spindles and the work are revolved on their own axes at the upper and 100 rear parts of the carrier, and are stationary while passing through the space between the belt-tightener 31 and the guide pulley 29, so as to afford a good facility for discharging the polished work and for taking 105 new work. The work is centered and discharged to much better advantage when the spindles do not revolve. When polished work is discharged from between rapidly revolving spindles it is thrown out violently 110 and is frequently bruised and dented.

The work to be sandpapered or polished,

such as chair legs and other similar articles, is placed in a magazine or hopper 35 arranged on the front side of the machine. The front part of the frame 2 has a longitudinal slot 36, and 37 are two brackets for supporting the magazine 35, secured by bolts 38 which engage with the slot 36 so that the position of the brackets may be varied and so that they may be set at different distances apart to suit different lengths of work. The brackets 37 have upwardly and rearwardly inclined arms 39 which form a portion of the magazine and support it so that the articles placed in it can slide downwardly by gravity. The articles are fed to the centering devices of the machine, hereinafter described, one by one, by means of two pairs of feeder fingers 40 and 41. These fingers are pivoted to the opposite ends of the lever 42 secured on a rock-shaft 43 which is journaled in the brackets 37. The fingers of each pair are projected and retracted alternately by means of a trip arm 44 secured on one end 25 portion of the rock-shaft 43. Pins 45 project from the carrier 20 and engage with the trip arm 44.

In Figs. 3 and 4 the full lines show the position of the parts after an article has 30 been discharged from the feeder into the machine. When the trip arm is moved by one of the pins 45 to the position shown in dotted lines in Fig. 3, the feeder fingers are moved to the position shown in Fig. 9. 35 The magazine is provided with adjustable guides 46, which retain the articles on its surface and permit them to slide down it. These guides are adjustable so that they will engage with articles of different size. In 40 order to adapt the fingers to articles of different widths, their upper end portions are made to slide in guide holes 47 and 48. The hole 47 is formed in a plate 49 secured to a bar 50 which is supported by the magazine 45 parallel to the rock-shaft 43. The plate 49 has a slot 51, and the hole 48 is formed in a separate plate 52 which is secured to the plate 49 by a bolt 53 which engages with the slot 51. The two plates 49 are slidable 50 on the bar 50 and have set-screws 54 for securing them after their positions have been adjusted. The plates 52 are adjusted on the plates 49 to vary the distance between the guide holes 47 and 48.

55 The articles discharged from the feeder slide one by one into the notched upper ends 56 of two stationary centering supports 57. These supports 57 are formed of flat bars which are secured against one side of the 60 upper end portions of arms 58 by bolts 59, and the arms 58 have vertical slots so that the centering notches can be adjusted vertically and pivotally. The lower end portions of the arms 58 are secured to the frame by bolts 65 60 which work in the slot 36 so that the arms

can be adjusted to suit articles of different length. The two arms are also connected together by means of a coupling-bar 62 having a longitudinal slot 63 and bolt 64 which engage with the arms and work in the said slot. When the centering arms have been adjusted to a preferred distance apart they are coupled by clamping them to the bar 62. Both arms can then be adjusted to different positions on the frame without changing the distance between them. These adjustments are beneficial because many articles are circular in parts and rectangular in other parts, and it is desirable to adjust the centering notches so that they will engage 75 with the circular or cylindrical parts of the work.

The dead spindles 25 of the carrier 21 are slidable in it, and are pressed toward the carrier 20 by springs 65. The spindles 25 85 have small rollers 66 and 67 journaled on pins 68 which project laterally from their end portions. The rollers 66 work in slots 69 in the carrier and prevent the spindles from revolving, and the rollers 67 project 90 into the path of a stationary cam plate 70 having an inclined surface 71. This cam plate is secured to the frame 2, and as the two carriers are revolved with the work held between their spindles, the rollers 67 are 95 retracted by the inclined portion of the cam plate at proper moments for releasing the work, that is to say after the work has ceased to be revolved by the belt 27. The articles then fall by gravity from between 100 the spindles, and slide down a curved plate or chute 73 to the rear side of the machine. The rollers 67 run upon the vertical portion of the cam plate, which holds the spindles retracted until the spindles come into the 105 correct position to take the articles from the centering supports. When each roller 67 leaves the cam plate, its spindle is shot into engagement with an article by the spring pertaining to its spindle, and the article is 110 centered between the two opposed spindles, and is moved upwardly by the revolving carriers into engagement with the sandpaper.

The sandpaper 75, or other similar abrasive material, is secured to brushes 76. 115 These brushes may be formed of broom corn, or other fiber, or they may be pads of soft material, and any devices which will support the abrasive material in contact with the irregular surface of the work. These brushes are mounted pivotally by shafts or rods 77, which are carried by curved supporting standards 78. These standards 78 are pivoted on a shaft 79 at the rear of the 120 frame 2, and are normally secured in a raised position by any approved fastening or clamping devices, 85. The standards may be slid longitudinally on the shaft 79 to adjust them to articles of different length, 125 130

and the standards may be unclamped and tilted to renew the sandpaper. The shafts 77 which support the brushes are arranged parallel to the main shaft, at predetermined 5 intervals apart, on the arc of a circle and at the rear side of the carriers. The sandpaper is secured to the brushes by any approved form of clamps or fastening devices, so that it can be renewed with facility as it becomes 10 worn, and sandpaper of different fineness is secured to the different brushes, so that the work may be first operated on by the coarse sandpaper and then polished by the finer sandpaper. The brushes are pressed toward 15 the work by means of springs 80 secured to arms 81 at one end and to one of the standards at the other end, and the said arms 80 are secured on the shafts or rods 77.

The articles are placed in the magazine, 20 and are fed one by one automatically onto the centering supports which are stationary. The articles are taken from the stationary centering supports by the spindles of the work carriers, and are carried around by 25 them and are pressed against the abrasive material on the brushes. The articles are revolved rapidly by the belt 27 before they touch the abrasive material 75, and they are kept in rapid revolution by the said belt 30 until after they leave the abrasive material of the last brush of the series. The articles then cease revolving and drop from between the carrier spindles in a finished condition when the dead spindles are retracted.

35 What I claim is:

1. In a sandpapering machine, the combination, with revoluble carriers provided with spindles arranged in a circle and adapted to support the work, of supports for abrasive 40 material arranged in the path of the work, automatically disengageable driving mechanism adapted to revolve the work on its own axis during one portion of each revolution of the carriers and while in contact with the 45 abrasive material and then permitting it to stop revolving, and means for releasing the work from the spindles during the remaining portion of each revolution of the carriers after it has been moved out of contact 50 with the abrasive material and has ceased to revolve.

2. In a sandpapering machine, the combination, with revoluble carriers provided with spindles arranged in a circle and adapted to 55 support the work, of abrasive devices arranged in the path of the work, driving mechanism operating to revolve the spindles on their own axes while the work is in contact with the abrasive devices and then permitting them to stop revolving, and means for releasing the work from the said spindles 60 while they are not being revolved on their own axes by the said driving mechanism.

3. In a sandpapering machine, the combination, with revoluble carriers provided with 65

spindles arranged in a circle and adapted to support the work, and belt pulleys secured to the spindles of one of the carriers; of supports for abrasive material arranged in the path of the work, a driving pulley, 70 a belt passing around all the said pulleys and operating to revolve the work on its own axis, and means for holding the said belt out of engagement with certain of the pulleys during a portion of the revolution of 75 the carriers.

4. In a sandpapering machine, the combination, with revoluble carriers provided with spindles arranged in a circle and adapted to support the work, and belt pulleys secured 80 on the spindles of one of the carriers; of supports for abrasive material arranged in the path of the work, centering supports for holding the work in a position to be engaged by the said spindles, a driving pulley, a belt 85 passing around all the said pulleys and operating to revolve the work on its own axis, and means for holding the said belt out of engagement with certain of the pulleys during a portion of the revolution of the carriers, to permit the work to be engaged by and discharged from the said spindles when it is not being revolved an its own axis and is not in contact with the abrasive material. 90

5. In a sandpapering machine, the combination, with revoluble carriers provided with spindles arranged in a circle and adapted to support the work, of stationary brackets, vertically and pivotally adjustable centering supports for holding the work in a position 95 to be engaged by the said spindles, and means for securing the centering supports to and pivoting them against one side of the upper end portions of the said brackets.

6. In a sandpapering machine, the combination, with revoluble carriers provided with spindles arranged in a circle and adapted to support the work, of a stationary supporting frame, brackets adjustable longitudinally of the frame and provided with means 100 for securing them to it, vertically and pivotally adjustable centering supports for holding the work in a position to be engaged by the said spindles, and means for securing the centering supports to and pivoting them 105 against one side of the upper end portions of the said brackets.

7. In a sandpapering machine, the combination, with revoluble carriers provided with spindles arranged in a circle and adapted to support the work, of a stationary supporting frame, brackets adjustable longitudinally of the frame and provided with means 110 for securing their lower end portions to it, a coupling-bar adjustably secured to the middle parts of the said brackets so that they can be adjusted separately or simultaneously, adjustable centering supports for holding the work in a position to be engaged 115 by the said spindles, and means for securing 120 the centering supports to and pivoting them against one side of the upper end portions of the said brackets.

8. In a sandpapering machine, the combination, with revoluble carriers provided with

the centering supports to the upper end portions of said brackets.

8. In a sandpapering machine, the combination, with revoluble carriers provided with spindles arranged in a circle and adapted to support the work, and stationary centering supports for holding the work in a position to be engaged by the said spindles; of a magazine for holding the pieces of work, feeding devices permitting the pieces to drop one by one from the magazine onto the centering supports, and trip mechanism operating the feeding devices automatically so that the pieces of work are fed at regular intervals and in proportion to the speed of the carriers.

9. In a sandpapering machine, the combination, with revoluble carriers provided with spindles arranged in a circle and adapted to support the work, and stationary centering supports for holding the work in position to be engaged by the said spindles; of a magazine for holding the pieces of work, feeding devices permitting the pieces to drop one by one from the magazine onto the centering supports, trip pins projecting from one of the carriers and arranged to correspond with its spindles, and a trip arm operated by the said trip pins and connected to the feeding devices so that the pieces of work are fed automatically at regular intervals and in proportion to the speed of the carriers.

10. In a sandpapering machine, the combination, with revoluble carriers provided with spindles arranged in a circle and adapted to support the work, and stationary centering supports for holding the work in position to be engaged by the said spindles; of a magazine for holding the pieces of work, feeding devices permitting the pieces to drop

one by one from the magazine onto the centering supports, said feeding devices being provided with reciprocating fingers and having adjustable guides for holding the feed fingers at various distances apart to suit pieces of work of different size, and trip mechanism operating the feeding devices automatically so that the pieces of work are fed at regular intervals and in proportion to the speed of the carriers.

11. In a sandpapering machine, the combination, with revoluble carriers provided with spindles arranged in a circle and adapted to support the work, of standards secured at the rear of the carriers, rods having their end portions mounted to oscillate in the standards, a series of supports for abrasive material secured to each of the said rods and arranged in the path of the work, arms secured to the said rods, and springs connected to the said arms and operating to move the rods and press the said supports toward the work.

12. In a sandpapering machine, the combination, with a supporting frame, and revoluble carriers mounted thereon and provided with spindles arranged in a circle and adapted to support the work; of standards having their lower ends pivoted to the frame and provided with means for holding them in a raised position, and yielding supports for abrasive material mounted to oscillate in the said standards and provided with means for pressing them toward the work.

In testimony whereof I have affixed my signature in the presence of two witnesses.

ALTON H. MATTESON.
